SHOE SOLE PRESS

Harry C. Short, Bartlesville, Okla.

Application May 23, 1934, Serial No. 727,159

3 Claims. (Cl. 12—36)

The present invention relates to new and useful improvements in presses for use particularly by repairmen when half soling men's shoes and has for its primary object to provide, in a manner as hereinafter set forth, a press embodying a novel construction through the medium of which the rear or shank portion of a half sole may be expeditiously cemented in position without misshaping the shoe while at the same time assuring a neat, attractive job.

Other objects of the invention are to provide a shoe sole press of the aforementioned character which will be comparatively simple in construction, strong, durable, highly efficient and reliable in operation, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a shoe sole press constructed in accordance with the present invention.

Figure 2 is a vertical sectional view, taken substantially on the line 2—2 of Figure 1, showing a shoe in position in the press.

Figure 3 is a horizontal sectional view, taken substantially on the line 3—3 of Figure 1.

Figure 4 is a vertical sectional view, taken substantially on the line 4—4 of Figure 3.

Figure 5 is a view in horizontal section, taken substantially on the line 5—5 of Figure 4.

Figure 6 is a view in vertical section, taken substantially on the line 6—6 of Figure 4.

Figure 7 is a detail view in perspective of one of the lasts.

Referring now to the drawings in detail, it will be seen that the embodiment of the invention which has been illustrated comprises a water container which is designated generally by the reference numeral 1, said container including a casting which is formed to provide a bottom 2 having outwardly extending flanges 3, end walls 4 having outwardly extending flanges 5, and an intermediate partition 6 defining compartments 7 for the reception of water. A flexible sheet 8 is mounted in the casting and said sheet is firmly secured to the flanges 3 and 5 and to the partition 6 in a manner to provide a leakproof joint through the medium of a metallic frame 9 of substantially U-shaped cross section having cut outs or openings 8 in the crown or arch thereof exposing the

flexible sheet or cover 8 with a surface configuration of an arch which substantially conforms to the shank portion of a shoe when placed across the arch. Bolts 11 secure the frame 9 to the flanges 3, 5 and the partition 6 with the flexible sheet or cover 8 therebetween. Pet cocks 12 are mounted in the end walls 4 for draining the container 1, said pet cocks being removable to permit the compartments 7 to be substantially filled with water.

Posts 13 rise from the container 1 and mounted thereon is a cross bar 14 in which vertical pressure screws 15 are threadedly mounted. Hand wheels 16 are fixed on the upper ends of the screws 15. The lower end portions of the screws 15 are engageable in removable socketed right and left lasts 17. Screws 15 are in alignment with the apex or zenith of the arch of cover 8 so the shank of a shoe can be centered on the arch across the water compartments 7.

From a consideration of the foregoing it is believed that the use of the press will be readily apparent, particularly to those skilled in the art to which the invention pertains. As suggested in Figure 2 of the drawings, the shoe are placed in position in the press with the yieldable, self-conforming supporting cushions provided by the flexible sheet 8 engaged in the shank portion of the shoe, the half sole 18, of course, being properly positioned. The shoe is designated by the reference numeral 19. The last 17 is then positioned in the shoe and the adjacent screw 15 is then threaded downwardly into said last for forcing the shoe downwardly in the press. It will thus be seen that pressure is applied to the shank portion only of the shoe for effecting the cementing thereto of the rear end portion of the half sole 18.

It is believed that the many advantages of a shoe sole press constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed.

Having thus described my invention, what I claim as new is:

1. A shoe sole press of the class described comprising a container for the reception of water, said container including a flanged bottom, flanged end walls, a partition rising from the bottom between the end walls, a covering of flexible material extending over the partition and the end 55

- walls, a frame of substantially U-shaped cross section mounted on the cover and secured to the bottom, the end walls, and the partition with said cover therebetween, said frame having openings in the crown thereof exposing the cover in the form of an arch, the exposed portions of the cover being engageable with and substantially conforming to the shank portion of a shoe, and means for pressing the shoe against the cover.
- 10 2. A shoe sole press of the class described comprising a container for the reception of water, said container including a flanged bottom, flanged end walls, a partition rising from the bottom between the end walls, a covering of flexible material extending over the partition and the end walls, a frame of substantially U-shaped cross section mounted on the cover and secured to the bottom, the end walls, and the partition with said cover therebetween, said frame having openings in the crown thereof exposing the cover in the form of an arch, the exposed portions of the cover being engageable with and substantially conforming to the shank portion of a shoe, and means for pressing the shoe against the cover,
- 15 20 25
- said means including posts rising from the container, a cross bar mounted horizontally on the

posts, pressure screws threadedly mounted in the cross bar, means for actuating the pressure screws, and lasts engageable in the shoes, said lasts having sockets therein for the reception of the screws.

3. A shoe sole press of the class described comprising a container for the receipt of water, a partition wall in the container dividing the interior thereof into twin water compartments, a flexible covering disposed over the container and 10 partition wall, a substantially U-shaped frame secured to the container and the partition wall securing the cover therebetween, portions of the frame being cut away about the crown on each side of the partition wall to provide openings in 15 the frame exposing a portion of the cover in the form of a transverse arch across the water compartments of the container, an upright frame connected with the container, and a pair of vertical last-carrying screws journaled in the upright frame, said screws disposed in alignment with the apex of the arch in the cover whereby 20 a shoe shank is pressed by the last transversely of the arch and across the water compartments of the container.

HARRY C. SHORT.
